[57] CLAIM

The ornamental design for a printer for electronic computers, substantially as shown and described.

DESCRIPTION

FIG. 1 is a front, top and right side perspective view of a printer for electronic computers showing our new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;
FIG. 7 is an enlarged fragmentary perspective view of the top, left corner of the printer, a cover of a control panel in an open position, the printer being fragmentarily shown for convenience of illustration;

FIG. 8 is a top, front perspective view of the printer, attachments being shown in broken lines for illustrative purposes only.
